CLAIM

The ornamental design of a vaporizer cartridge, substantially as shown and described.

DESCRIPTION

FIG. 1 shows a bottom, front, and side perspective view of a vaporizer cartridge that incorporates the new, original, and ornamental design;

FIG. 2 shows a top, front, and side perspective view thereof;

FIG. 3 shows a front plan view thereof; the rear plan view is the same;

FIG. 4 shows a side plan view thereof; the opposite side plan view is the same;

FIG. 5 shows a top plan view thereof; and,

FIG. 6 shows a bottom plan view thereof.

The broken lines show portions of the vaporizer cartridge that form no part of the claimed design.

1 Claim, 5 Drawing Sheets
